D. GRIEVE

DRAFTING ELLIPSOGRAPH

Filed Jan. 31, 1927.

Patented July 12, 1927.

1,635,270

UNITED STATES PATENT OFFICE.

DAVID GRIEVE, OF DETROIT, MICHIGAN.

DRAFTING ELLIPSOGRAPH.

Application filed January 31, 1927. Serial No. 164,719.

My invention relates to a drafting instrument and more especially to an instrument for delineating ellipses shown in the accompanying drawings and particularly described 5 in the following specification and claims.

This invention is designed as an improvement on the instrument shown in the Patent No. 1,415,547 issued to me May 11th, 1922, for a similar purpose.

10 One of the objects of the present invention is to produce an instrument simple in construction, of fewer parts, and less costly to manufacture.

A further object of the invention is to provide 15 a device having a wide range, and capable of describing ellipses of relatively smaller and greater major and minor axis than possible with the instrument to which reference has been made.

20 A further object of the invention is to provide a device in which the scribing point and the center post,—located at the intersection of the major and minor axis,—are yieldably supported so that when the hand 25 of the drafting rests upon the instrument the scribing point may readily follow any possible irregularities in the plane surface supporting the paper on which the drawing is to be executed.

30 With the foregoing and other objects in view which will appear as the description proceeds, the invention further resides in the combination and arrangement of parts and in the details of construction hereinafter 35 described and claimed, it being understood that changes may be made in the precise embodiment of the invention herein disclosed without departing from the spirit of the same.

40 In the drawings accompanying this specification:

Figure 1 is a perspective view of the instrument with a portion of its swinging beam broken away, showing an ellipse partially 45 described by the scribing point.

Figure 2 is a plan view of the instrument indicating in dotted lines an ellipse formed thereby.

Figure 3 is a fragmentary side elevation 50 on a relatively larger scale with parts in section to disclose the construction of the yieldable center post and the hinged and slidable connections between the different co-operating members of the device.

55 Figure 4 is a perspective view of a detail showing a slidable adjustable member car-

rying a pen-point which is designed to replace the pencil scribing point, when it is desired to ink a drawing.

Referring now to the letters of reference 60 placed upon the drawings:

A denotes an L-shaped bracket arm with its downwardly extending leg A¹ fitted with a transverse footpiece B, having spaced contact points B¹, B² for supporting the instrument upon a drafting board.

The lower end of the leg A¹ terminates in a wedge-shaped pointer A²,—the contact edge of which is on a plane with the contact points B¹, B² of the footpiece B and in use 65 is placed on a line indicating the minor axis of the ellipse to be described.

Projecting from the forward end of the L-shaped bracket arm is a wedge-shaped extension plate A³ welded or otherwise secured to the bracket arm with lugs A⁴, A⁵ at its flaring outer end secured to a transverse bar C by rivets or other fastening 70 means.

Rigidly secured to a bracket A^c projecting 75 downwardly from the underside of the wedge-shaped plate A³, is a bar D in spaced relation to the latter and extending outwardly in alignment with the L-shaped bracket arm.

80 Mounted upon the bar D is a slidable fitting E, having flanges overlapping the bar to maintain it in slidable co-operating relation therewith. A somewhat similar fitting F is pivoted to the slidable fitting E by a bolt 90 G, through a fiber washer G^a,—which insures a free swinging movement between the fittings without "seizing."

85 The fitting F is provided with a thumb screw F¹ to secure it when adjusted to a 95 swinging bracket arm H supporting a beam I, located below in spaced alignment with the bracket arm and rigidly secured to the latter.

The bracket arm H is pivoted to a slidable fixture J mounted upon the transverse bar C secured to the wedge-shaped bracket extension and is free to slide thereon.

100 The bracket arm H and fitting J are pivoted together by a screw J¹ extending through a fiber washer J^a, employed to insure the parts against "seizing" through an over-tight adjustment of the screw.

105 Mounted upon the swinging beam I is a slidable fixture K, secured to the beam when 110 adjusted by a thumb screw K¹, on the end of a transverse bolt extending across the

fixture—which is slotted longitudinally for a portion of its length as indicated at K^a,— whereby the thumb screw when adjusted may clamp the fitting securely to the swing-
5 ing beam.

L is a tubular post tapped at its upper end to receive a screw-threaded plug M depending from the fitting K. N is a plunger housed in the post having an enlarged head 10 N¹, overlapping a shoulder in the post to limit its downward movement. The plunger N has also a downwardly projecting tubular stem N^a into which is inserted a pencil or other scribing point,—the pencil being 15 held by the resilient action of the walls of the stem which are slotted (N^b) at its lower end.

P is a coil spring bearing against the plunger at one end and the plug M at the other to maintain the scribing point at the limit of its movement but which is free to yield under the hand of the draftsman.

Q is a center post screwed into the bar D and is recessed at its lower end to receive a yieldable plunger R,--fitted with a pivot needle S in its projecting end.

The wall of the tubular post Q is flanged as at Q¹, to overlap a shoulder formed in the plunger R to limit its outer movement.

30 T is a spring coiled upon a stem of the plunger which bears against a shoulder on the latter and the wall of the post, the purpose being to provide a yieldable point under pressure of the draftsman's hand to 35 adapt the device for work over irregular surfaces.

To set the instrument for describing an ellipse of given major and minor axes;—
the intersecting lines X and Y are first laid out by the draftsman with the maximum length of the major and minor axis of the proposed ellipse indicated on the respective lines.

The swinging beam I is then turned in exact alignment with the bracket bar A with the pivot needle S, supported by the post Q, at the intersection of the major and minor axis and with the wedge-shaped end A² of the bracket arm A resting on the line of the minor axis.

The fitting K on the swinging beam I is then adjusted so that the scribing point carried by the post L rests on the point indicating the limit of the minor axis,—being one-half of the width of the minor axis of the proposed ellipse, from the pivot needle S at the intersection of the major and minor axes.

60 The thumb screw F^1 for securing the fitting F to the bracket arm H is then released that the fitting may slide upon the bracket arm. The swinging beam I with the scribing point carried by the plunger N , is then shifted that the scribing point may rest on the limit of the major axis,—the same being

one-half of the length of the major axis of the proposed ellipse from the intersection of the minor axis.

The set screw F^1 is then adjusted to secure the fitting F fixedly to the bracket H . The instrument is now in condition to describe the proposed ellipse. 70

The swinging beam is then swung to a position adjacent and parallel with the L-shaped bracket arm A, with the scribing point carried by the plunger N in contact with the paper at the point noted, the same being one-half the minor axis from the intersection of the major axis of the proposed ellipse. 80

The swinging beam is now turned so that its scribing point may delineate the proposed ellipse upon the paper,—the scribing point in its journey traversing the points indicating the extreme major and minor axes of the ellipse. 85

To delineate an ellipse of greater length or breadth, the instrument has only to be adjusted with reference to the major and minor axis of the ellipse, in the manner indicated, to describe the proposed figure. 90

Having thus described my invention what I claim is:

1. In an instrument of the class described, a supporting bracket having means adapted to register with a line representing one axis of an ellipse; a transverse bar secured to the projecting end of said supporting bracket; a bar parallel with and rigidly secured to the supporting bracket in spaced relation to the latter; a slidable element adapted to traverse the transverse bar; a swinging beam provided with a bracket arm parallel to and spaced from the beam; means for pivoting the slidable element carried by the transverse bar to the bracket of the swinging beam; a pair of elements pivoted to each other and respectively slidably mounted upon the bar rigidly secured to the supporting bracket and the bracket arm of the swinging beam, said slidable element carried by the bracket arm of the swinging beam having means for securing it to said arm when adjusted; a post rigidly secured to the bar carried by and parallel with said supporting bracket; and an adjustable slidable element fitted with a scribing point mounted upon the swinging beam including means for securing said fitting when adjusted to the swinging beam. 120

2. In an instrument of the class described, a supporting bracket having means adapted to register with a line representing one axis of an ellipse; means for supporting said bracket arm in spaced relation to the surface on which the ellipse is to be delineated; a transverse bar secured to the projecting end of said supporting bracket; a bar parallel with and rigidly secured to the supporting bracket in spaced relation to the latter: 130

a slidable element adapted to traverse the transverse bar; a swinging beam provided with a bracket arm parallel to and spaced from the beam; means for pivoting the slidable element carried by the transverse bar to the bracket of the swinging beam; a pair of slidable elements pivoted to each other and respectively mounted upon the bar rigidly secured to the slidably supporting bracket and to the bracket arm of the swinging beam, the slidable element carried by the bracket arm of the swinging beam being provided with means for securing the slidable element to said arm when adjusted; a post rigidly secured to the bar parallel 15 with and carried by said supporting bracket; a resiliently supported pivot mounted in said post; an adjustable slidable element mounted upon the swinging beam; a scribing point; resilient means for yieldably supporting said scribing point in the slidable element; and means for securing said slidable element when adjusted to the swinging beam.

In testimony whereof, I sign this specification.

DAVID GRIEVE.
